(57) **CLAIM**

The ornamental design for an analyzer, as shown and described.

DESCRIPTION

FIG. 1 is a front, left side perspective view of an analyzer.

FIG. 2 is a bottom, left side perspective view thereof.

FIG. 3 is a top plan view thereof.

FIG. 4 is a bottom plan view thereof.

FIG. 5 is a front elevational view thereof.

FIG. 6 is a left side elevational view thereof. The right side is a mirror image of the left side.

FIG. 7 is a rear elevational view thereof.

FIG. 8 is a front, left side perspective view of the analyzer with a front door thereof open. Notably, a portion of a sample holder rotor is visible.

FIG. 9 is a bottom, left side perspective view thereof.

FIG. 10 is a top plan view thereof.

FIG. 11 is a bottom plan view thereof.

FIG. 12 is a front elevational view of the analyzer with the front door thereof open. Notably, a portion of the sample holder rotor is visible.

FIG. 13 is a left side elevational view of the analyzer with the front door thereof open. The right side is a mirror image of the left side; and,

FIG. 14 is a rear elevational view of the analyzer with the front door thereof open.
